Fig. 3.

To all whom it may concern:

Be it known, that I, Carl W. Sundberg, a citizen of the United States of America, and residing at Ferndale, in the county of Oakland and State of Michigan, have invented a new, original, and ornamental Design for an Electric Motor, of which the following is a specification, reference being had to the accompanying drawings, forming part thereof, and in which:

Figure 1 is a perspective view of an electric motor, embodying my new design;

Figure 2 is a top plan view of the end caps shown in Fig. 1; and

Figure 3 is a vertical sectional view of said cap taken generally on the plane of line 3—3 in Figure 2.

The dominant features of my design reside in those portions thereof illustrated in full lines.

I claim:

The ornamental design for an electric motor, as shown and described.
